US00D999727S

(12) **United States Design Patent** (10) **Patent No.:** **US D999,727 S**
Wu (45) **Date of Patent:** **** Sep. 26, 2023**

(54) **CHARGER**

(71) Applicant: **Anker Innovations Technology Co., Ltd.**, Changsha (CN)

(72) Inventor: **Xiangpeng Wu**, Shenzhen (CN)

(73) Assignee: **Anker Innovations Technology Co., Ltd.**, Changsha (CN)

(**) Term: **15 Years**

(21) Appl. No.: **29/812,631**

(22) Filed: **Oct. 22, 2021**

(30) **Foreign Application Priority Data**

Apr. 27, 2021 (CN) 202130247429.1

(51) **LOC (14) Cl.** **13-02**

(57) **CLAIM**

The ornamental design for a charger, as shown and described.

DESCRIPTION

FIG. 1 is a front top perspective view of a charger showing my new design in a closed state;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front top perspective view of the charger of FIGS. 1-8 in an open state;

FIG. 10 is a front view thereof;

FIG. 11 is a left side view thereof, the right side view being a mirror image thereof; and,

FIG. 12 is a top view thereof.

The broken lines in the Figures are for the purpose of illustrating portions of the charger that form no part of the claimed design.

1 Claim, 12 Drawing Sheets
